UNITED STATES PATENT OFFICE.

MAX BUCHERER, OF BERLIN-REINICKENDORF-WEST, GERMANY.

PUMP.

Application filed June 23, 1922. Serial No. 570,421.

To all whom it may concern:

Be it known that I, MAX BUCHERER, a citizen of Germany, residing at Berlin-Reinickendorf-West, Germany, have invented certain new and useful Improvements in Pumps, for which I have filed application in Germany, October 20, 1916, of which the following is a specification.

My invention refers to pumps and more especially to feed pumps or injection pumps for liquid fuels such as benzine and the like serving for driving internal combustion engines.

It is an object of my invention to provide a pump capable of injecting under pressure or of atomizing in the combustion chamber or cylinder or the like or in the pipe leading thereto minute quantities of a liquid such as liquid fuel and which may amount to not more than the fraction of a drop in each case, this being done with an extraordinarily high speed and exactness.

It is a further object of my invention to provide a pump which is capable of conveying always the same quantity of liquid such as fuel independently of the number of rotations of the engine shaft and without regard to the minuteness of the quantities of fuel fed in rapid succession.

It is a further object of my invention to provide a pump which will convey liquid with the least expenditure of power and nevertheless with great speed and absolute uniformity and which consists of so few and so simply actuated parts that it will not easily get out of order but will remain permanently operative.

These and other objects of my invention will appear from the following description thereof together with the drawings which illustrate my invention by way of example as embodied in a fuel feed pump for internal combustion engines.

I wish it to be understood that my invention is neither restricted to the details of construction nor to the combination of all the parts disclosed in the drawings, nor to pumps serving for the supply of fuel, for the means of imparting motion as well as other parts of mechanism shown in the drawing might as well be replaced by similar parts and the pump might as well be used for other liquids than fuel without departing from the spirit of my invention.

55 In the drawing:

Fig. 1 is a vertical section, partly in ele-

vation, of the pump casing and the pump proper on the line 1-1 in Fig. 2 as viewed from the left in Fig. 2.

Fig. 2 is a vertical section at right angles 60 to the one in Fig. 1 taken on the line 2-2 in Fig. 1.

Fig. 3 is a longitudinal section of the fuel feed system taken on the line 3-3, the pump casing cover being shown in elevation. 65

Fig. 4 is a plan view from below of the driving mechanism.

Fig. 5 is an elevation and

Fig. 6 is a vertical section of one of a pair of perforated discs disposed in the 70 pump casing and serving for limiting the movements of the diaphragm arranged between them.

Fig. 7 is a diagram drawn to a reduced scale and disclosing an arrangement of the 75 pump as used for instance in connection with motor cars together with the fuel tank placed under constant pressure.

Referring to the drawing, 1, 2 is the pump casing in two parts, part 1 being fixed 80 by aid of threaded bolts on top of a box 3 surrounding the driving mechanism. Part 1 of the pump casing enclosing the pistons has a chamber 4 of T-shaped section which is separated from part 2 by a portion or 85 diaphragm 5 capable of deformation. This diaphragm which may consist of some suitable more or less elastic material, amongst others thin sheet metal, is fixed in position between a pair of perforated discs 6 vaulted 90 in opposite direction, such discs being held with their edges between parts 1 and 2 of the pump casing. The two perforated discs 6 allow the middle portion of the diaphragm 5 to be moved to either side so as to apply 95 itself against one of these discs which thus serve to prevent the diaphragm from being overstrained or destroyed by an undue pressure which might arise.

In the solid rear wall of part 1 of the 100 casing there are arranged the cylindrical borings 7 and 8 serving to guide two pistons 9 and 10 of small diameter which are reciprocated therein by the driving mechanism to be described further below. The 105 chamber 4 and that portion of the cylindrical borings 7 and 8 that is not occupied by the pistons 9 and 10 is filled with a liquid such as oil, glycerine or the like, while the chamber 11 in the part 2 of the casing is 110 filled with the liquid such as liquid fuel to be conveyed.

This description shows that the pump has the form of a diaphragm pump with a liquid piston acted upon in well known manner by two solid pistons one of which 5 serves as working piston, the other one as compensating piston.

According to the present invention the chambers 4 and 11 of the pump casing as well as the fuel supply and discharge pipes 10 connected therewith are permanently placed under constant pressure. In applying this 15 pump to stationary uses this may be effected for instance by placing the fuel tank high above the pump, thus providing a high column of liquid fuel which exerts pressure 20 on the fuel contained in chamber 11. In applying my invention to moveable uses such as motor vehicles I prefer employing a container such as 14 filled with gas or 25 air under pressure and which is connected with the interior of the fuel tank 12 by a pipe 13, a reducing valve being inserted between the container 14 and the pipe 13 as usual. The gas pressure acting on the liquid in the fuel tank 12 acts towards placing the liquid in chamber 11 under constant pressure.

The fuel is fed from the fuel tank 12 through an admission pipe 16 into the head 30 portion 17 of the pump which is provided with a longitudinal boring 18 for the admission and a longitudinal boring 19 for the discharge of the fuel. The admission boring 18 extends upwards in the middle 35 portion of the head 17 and this upwardly extending part 20 is closed by a ball valve 22 loaded with a spring 21. From the valve chamber 23 a boring 24 leads to the fuel discharge boring 19 which has the pipe 25 leading to the cylinder or the like connected to it. Near the end of this pipe there is again arranged a ball valve 26 pressed on its seat by a spring 27.

From the point of intersection of the 40 bорings of channels 19 and 24 a downward directed channel 28 leads to the chamber 11. Provided that the spring load lasting on each of the two ball valves 22 and 26 be equal to the gas pressure lasting on the 45 fuel to be conveyed, so long as the two pistons 9 and 10 give away to one another to an equal extent, in other words, if the two pistons have equal diameters and move with equal velocity in opposite directions, the diaphragm 5 is held in its normal position and no fuel will flow through the channels 16 and 25. However, if the two pistons 9 and 10 are imparted an unequal motion, one of them, such as piston 10, ending 50 its stroke sooner than the other piston, in other words, if piston 10 has a shorter stroke than piston 9, then the substantially constant quantity of oil or glycerin in the chamber 4 will be forced against the diaphragm. This will cause this latter to bulge

into the chamber 11. In consequence of the increased pressure created thereby in chamber 11, the discharge valve 26 will now be lifted from its seat and some fuel will be forcibly discharged from the channel 25. On 55 the two pistons 9 and 10 now moving in opposite direction, the working piston 9 is first displaced the difference between the strokes of the two pistons and only thereafter the compensating piston 10 will rise. 60 As the working piston 9 starts on its return stroke, the entire quantity of oil or glycerin is free to move back into the chamber 4 and, in consequence thereof, the diaphragm will return to its normal position. In chamber 11 there is now room for a fresh quantity of fuel equal to the quantity ejected through the discharge valve. The gas pressure lasting on the admission valve 22 causes the fuel in the pipe 16 to lift the valve 22 and the fuel in chamber 11 is thus filled up under pressure.

As will be seen from the foregoing description, my novel pump in contradistinction to other pumps does not draw liquid 65 into the pump chamber by suction, but the substantially constant pressure acting on the liquid in the feed pipe well, as soon as, in consequence of some of the liquid in the pump chamber 11 having been ejected through the discharge valve, the pressure diminishes, slightly fill up the liquid in the pump chamber. With regard to easily volatile or gas containing liquid, such as liquid 70 fuel, this mode of working entails the great advantage that the liquid to be conveyed is permanently subjected to a substantially equal pressure whereby a volatilization of the liquid or the separation of air, gases or vapours and the formation of bubbles connected therewith is absolutely prevented from taking place. Obviously, a formation of bubbles 75 would cause the conveying of liquid to come to a standstill, inasmuch as the pistons in moving up and down would merely alternately compress the little quantity of air, gas or vapour and allow it to expand again.

In the modification shown in the drawing, the pistons 9 and 10 are positively actuated by a double arm rock lever 29, 30, 80 rocking about a horizontal axle 28 underneath the pistons, said lever causing the pistons to rise against the action of springs 33 tending to hold them in depressed position.

The arm 29 of the rock lever acts on piston 9, the arm 30 on piston 10. However, the rock lever does not act on the pistons direct, 85 cylindrical members 31 closed at the lower end and movable in cylindrical sleeves 32 being inserted between the arms of the lever and the pistons and adapted to reciprocate vertically against the action of the springs 33. The sleeves 32 are in contact with the 90

walls of the borings 34 of the pump casing. The members 31 are linked to the pistons 9 and 10, a link 35 having its ends hollowed out spherically embracing a spherical knob 5 36 on each piston and a similar knob 37 on the bottom of a member 31. Rollers 38 are pivoted to the arms 29 and 30 of the rock lever and are applied from without against the members 31. Another roller 40 carried 10 by a branch 39 of the arm 29 is pressed against the cam face of the eccentric 41 fixed on the horizontal driving shaft 42 by aid of a coil spring 43 having its other end attached to a screw bolt 44 arranged in the 15 bottom of the box 3.

The cam of the eccentric 41 is so shaped that the rock lever alternately gives way and presses upwards respectively one or the other member 31. If the arm of the rock 20 lever moves downwards, then the respective member is pressed downwards by its spring 33 and pulls its piston along. On the other hand, the positive pressure of the arms of the rock lever causes the pistons to alternately rise against the action of springs 33. 25

The descending movement of the member carrying the compensating piston 10 is limited by a stop which in the modification disclosed in the drawing has the form of a 30 threaded spindle 45 guided in a nut 46 and a stuffing box 47 at the bottom of box 3 and the upper end of which extends into the path of the respective member, so that, as this member meets the stop, the down stroke 35 of the compensating piston comes to an end, while the working piston is free to still finish its upward movement. By turning the spindle 45 the downstroke of the compensating piston 10 and with it the quantity to 40 be conveyed by the pump per stroke can be varied within wide limits.

In order that the oil or the like contained in the chamber 4 be filled up again in case that some of it should escape from the chamber past one of the pistons 9 or 10 an oil 45 filled tube 48 is arranged in the head of the pump casing, said tube being closed by a non return valve 49 placed under the pressure of a spring equalling the pressure prevailing 50 in the interior of the pump. As soon as the quantity of oil in the chamber 4 should diminish unduly, the valve 49 will be somewhat relieved and will allow the same quantity of oil to enter chamber 4.

55 As described above, my novel pump does not convey any liquid during the greater part of the piston stroke. The ascending piston 9 merely displaces the oil or the like within the chamber 4 and forces it into the boring or cylinder of the receding piston 10. Only after this latter piston has been brought to a standstill by meeting the stop, the short portion of the upward stroke which is still left for the working piston 9, causes 60 a sudden ejection of a more or less minute

quantity of liquid subjected to constant pressure.

While in ordinary high speed pumps the valves, owing to the severe strains placed thereon, are subject to early destruction, the 70 valves in the novel pump according to the present invention are merely acted upon by the pressure of their springs which is only slightly higher than the gas pressure acting on the liquid. In consequence thereof the 75 valves in opening have to overcome and are forced back into their seats only by this small difference in pressure so that, although the pump be run with more than 1000 revolutions per minute, the valves can never be 80 overstrained and will last almost indefinitely.

The pistons 9 and 10 being permanently lubricated by the oil in the chamber 4 do not even come in contact with the cylinder walls, but are continually covered with a 85 film of oil whereby friction is reduced to a minimum.

I claim:—

1. A pump comprising in combination, a 90 pump casing, means for holding said casing under constant increased pressure, a piston movable relatively to the interior of said casing and means for causing said piston to convey liquid under pressure only during the latter part of its conveying 95 stroke.

2. A pump comprising a piston and means for causing said piston to convey liquid under substantially constant pressure only near the end of its conveying stroke. 100

3. A pump comprising in combination, a pump casing, a diaphragm within said casing dividing it in two chambers, one of said chambers being filled with a substantially constant quantity of a liquid, admission and discharge ports in the other chamber for the liquid to be conveyed, two pistons movable in said first chamber, and means for forcing one of said pistons into said first chamber, so as to cause the other piston 110 to give way in opposite direction, said other piston having a shorter stroke than said first piston.

4. A pump comprising in combination, a 115 pump casing, a diaphragm within said casing dividing it in two chambers, one of said chambers being filled with a substantially constant quantity of a liquid, admission and discharge ports in the other chamber for the liquid to be conveyed, two pistons movable in said first chamber, means for forcing one of said pistons into said first chamber, so as to cause the other piston to give way in opposite direction and displaceable means for arresting said other piston, before said first piston has completed its 120 stroke.

5. A pump comprising in combination, a 125 pump casing, a diaphragm within said casing dividing it in two chambers, one of said

chambers being filled with a substantially constant quantity of liquid, admission and discharge ports in said other chamber, non return valves closing said ports, means for holding said chambers, said ports and said valves under a substantially constant increased pressure slightly inferior to the valve pressure and means for displacing the substantially constant quantity of liquid in said first chamber, so as to force said diaphragm towards said other chamber and thereby to cause one of said valves to open.

6. A pump comprising in combination, a pump casing, a diaphragm within said casing dividing it in two chambers, one of said chambers being filled with a substantially constant quantity of liquid, admission and discharge ports in said other chamber, non return valves closing said ports, means for holding said chambers, said ports and said valves under a substantially constant increased pressure slightly inferior to the valve pressure, two pistons movable in said first chamber, and means for forcing one of

said pistons into said first chamber, so as to cause the other piston to give way in opposite direction, said other piston having a shorter stroke than said first piston.

7. A pump comprising in combination, a pump casing, a diaphragm within said casing dividing it in two chambers, one of said chambers being filled with a substantially constant quantity of liquid, admission and discharge ports in said other chamber, non return valves closing said ports, means for holding said chamber, said ports and said valves under a substantially constant increased pressure slightly inferior to the valve pressure, two pistons movable in said first chamber, means for forcing one of said pistons into said first chamber, so as to cause the other piston to give way in opposite direction, and means for arresting said other piston, before said first piston has completed its stroke.

In testimony whereof I affix my signature.

MAX BUCHERER.
